US0D1050891S

(12) **United States Design Patent** (10) **Patent No.:** **US D1,050,891 S**
(45) **Date of Patent:** **** Nov. 12, 2024**

(54) **CUP LID**

(71) Applicant: **Waddington North America, Inc.**,
Chelmsford, MA (US)

(72) Inventor: **Russell L. Simms, II**, Cleveland, TN
(US)

(73) Assignee: **Waddington North America, Inc.**,
Chelmsford, MA (US)

(**) Term: **15 Years**

(21) Appl. No.: **29/850,012**

(22) Filed: **Aug. 16, 2022**

Related U.S. Application Data

(62) Division of application No. 29/683,023, filed on Mar.
11, 2019, now Pat. No. Des. 964,168.

(57) **CLAIM**

The ornamental design for a cup lid as shown and described.

DESCRIPTION

FIG. 1 is a front, top, and right side perspective view of a cup lid, showing our new design;

FIG. 2 is a front, bottom and left side perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a right side elevational cross-sectional view thereof
taken in the direction of the cut line 9-9 indicated in FIG. 3;
and,

FIG. 10 is a right side elevational cross-sectional view
thereof taken on the cut line 10-10 indicated in FIG. 3.

Features of the cup lid that are illustrated by broken lines
form no part of the claimed design.

1 Claim, 10 Drawing Sheets
